UNITED STATES PATENT OFFICE.

JOHN MCNEIL, OF CINCINNATI, OHIO, ASSIGNOR TO THE JOHN DOUGLAS COMPANY,
OF CINCINNATI, OHIO, A CORPORATION OF OHIO.

AUTOMATIC FLUSH-VALVE.

1,355,988.

Specification of Letters Patent.

Patented Oct. 19, 1920.

Application filed March 29, 1917. Serial No. 158,176.

To all whom it may concern:

Be it known that I, JOHN MCNEIL, a citizen of the United States of America, and resident of Cincinnati, in the county 5 of Hamilton and State of Ohio, have invented a new and useful Improvement in Automatic Flush-Valves, of which the following is a specification.

An object of my invention is to produce 10 an improved automatic flush valve for tanks, in which corrosion of the parts will not affect the operation of the valve.

This and other objects are attained in the construction described in the following 15 specification and illustrated in the accompanying drawings, in which:

Figure 1 is a cross sectional view of a tank disclosing a valve embodying my invention, mounted therein.

20 Fig. 2 is a view of the parts disclosed in Fig. 1, but showing the valve elements moved to different positions.

Fig. 3 is a sectional view taken on the line 3—3 of Fig. 1.

25 Fig. 4 is a sectional view taken on the line 4—4 of Fig. 1.

Fig. 5 is a detail sectional view of a pivot joint of my improved valve.

My improved valve consists of a siphon 30 5 having one of its branches 6 extending through the bottom of the tank and provided with any suitable means, such as the screw threads 7, for connection with the pipe adapted to conduct the flush water 35 from the tank, the opposite branch 8 of the siphon extending to a point adjacent to the bottom of the tank and adapted to be uncovered by the valve 9 to permit the water to enter the siphon and to be discharged 40 therethrough. Valve 9 is loosely mounted upon an arm 10 pivotally mounted at a point 11 on a bracket 12 extending from the lower end 13 of branch 8 to the siphon. Arm 10, at its pivot point 11, is loosely 45 mounted. Valve 9 consists of a disk 14 of rubber or other suitable yielding material having washers 15 and 16 upon its respective upper and under sides. These washers are materially smaller in diameter than the 50 opening of end 13 of siphon 5, so that the yielding material of valve disk 14 will yield when the valve is brought to its closed position and be held therein by the pressure of the water in the tank. Pivot pin 17 of 55 valve 9 is very loosely mounted so that the

valve may seat itself without difficulty when moved to its closed position. Opposite bracket 12, a lug 18 is formed on end 13 of siphon 5. This lug is adapted to carry guides 19 and 20 which extend downwardly and guide arm 10 in its upward and downward movements, so that valve 9 may be moved to register properly with the opening in end 13. These guides are of sufficient distance apart to permit of free 60 movement of arm 10, so that no corrosion of the metal thereof will render the valve inoperative by causing its parts to stick. The movable end 21 of arm 10, is pivotally connected at a point 22, with the lower end 65 23 of a yoke or fork 24. The pivotal connection 22, like connections 11 and 17, is also a very loose one. One branch 25 of yoke 24 including an upwardly extending rod 26 is reciprocally mounted in a lug 27 70 75 extending from the top 28 of siphon 5, stop nuts 29 being provided on the rod for limiting the downward movement of yoke 24. The mounting of rod 26 in lug 27 is also a very loose one. Between branches 25 and 20 30 of yoke 24, a rod 31 is located, the rod being loosely mounted in the ends of branches 25 and 30. Upon rod 31 and rigidly connected therewith is mounted a cup 32, adapted when empty to act as a float 80 by means of which valve 9 is lifted to its closed position, and when filled to act as a weight by means of which the valve is opened. Secured to one side of cup 32 is a hollow member 33 adapted to act as an 85 air chamber to increase the buoyancy of cup 32 and also to restore the cup to such a position that it may act as a float. Located below rod 31 is a pin 34 extending from one side of the cup and adapted to 90 engage the opposite side of branch 25 of yoke 24 from that on which member 33 is located. The purpose of this pin will be hereinafter more fully described. Extending into the tank is a pipe 35 adapted to 95 conduct the water with which the tank is filled, a valve 36 being located at the upper end of the pipe for controlling the rate of delivery of water to the tank.

In describing the operation of my improved automatic flush valve, the tank will 100 be considered as having been filled, the parts of the valve having been brought to occupy the positions disclosed in Fig. 1. In this condition, the water level is increased until 105 110

the water overflows into the cup as disclosed in Fig. 4. As soon as the cup has been sufficiently filled to overcome its buoyancy, it sinks, its weight and that of yoke 24 and its 5 connected parts, causing valve 9 to open against the pressure of water in the tank. Since the water level, at this time is above the top 28 of siphon 5, the water rises rapidly in branch 8 of the siphon and passes over 10 into branch 6. The fall of the water through branch 6 then produces the siphonic action, causing the water in the tank to be withdrawn until the open end of branch 8 is reached. As the water level drops to its 15 position, hollow member 33 of cup 32 also drops, gradually tipping the cup and emptying its contents. This brings the cup to the position disclosed in Fig. 2, which figure also shows the water level after operation 20 of the siphon has taken place. Since the delivery of water to the tank through valve 36, is constant, the water level within the tank is gradually increased. As the water rises, member 33 of cup 32 floats upon the 25 surface and gradually restores the cup to its upright position, stop pin 34 gradually being brought to engage branch 25 of yoke 24 to prevent the cup being moved beyond its normal vertical position such as disclosed 30 in Figs. 1, 3 and 4. Simultaneously with its restoration to its normal position, the cup lifts yoke 24 and through arm 10 also lifts valve 9 to bring it into engagement with the open end of branch 8 of the siphon. Since 35 valve disk 14 is of yielding material and since valve 9 is loosely mounted on pin 17 upon arm 10, it is caused to seal the opening of branch 8 quickly and effectually. This prevents the passage of water through the 40 siphon, the parts being so designed that the valve is closed before the water level reaches the point of overflowing from branch 8 to branch 6 of the siphon. As soon as the parts 45 have been restored to the position disclosed in Figs. 1 and 2, the water level gradually rises to overflow into the cup as disclosed in Fig. 4 for the purpose of again repeating the above described operation of emptying

the contents of the tank. The periodical operation of the valve may be regulated by 50 controlling the delivery of water to the tank by means of valve 36, the requirements of the apparatus to which the discharge branch 6 of siphon 5 is connected, governing this 55 regulation.

In my improved construction I have designed a flush valve in which all of the pivot pins as well as all parts where reciprocation occurs, can not be affected by an accumulation of corrosion by which the 60 valve may stick and be rendered inoperative. In addition to this I have provided a valve disk which is of such a yielding 65 nature that particles of corrosion which may accumulate thereon and on the opening it is adapted to close, will not effect the sealing thereof against the seepage of water between it and the siphon.

Having thus described my invention, what 70 I claim is;

The combination of a tank and an automatic flush valve comprising a siphon, a guide secured to the siphon adjacent to its top, a bracket mounted upon the siphon adjacent to its mouth, a guide secured to the 75 siphon opposite to the bracket, an arm pivoted to the bracket engaging the second mentioned guide, branches extending from the free end of said arm, one of said branches adapted to engage the first mentioned guide, a float pivotally engaging said branches and adapted to be capsized by the emptying of the tank and to be righted by the filling of the tank, a pin mounted upon the arm beneath the mouth of the siphon 80 and a flexible disk secured upon the flange and of a diameter greater than the diameter of the mouth of the siphon.

In testimony whereof, I have hereunto 85 subscribed my name this 27th day of March, 1917.

JOHN McNEIL.
